UNITED STATES PATENT OFFICE.

ERASTUS L. STOCKMAN, OF ADAMS, NEBRASKA.

PORTABLE WATER SUPPLY AND HEATING SYSTEM.

1,027,928.

Specification of Letters Patent.

Patented May 28, 1912.

Application filed August 4, 1910. Serial No. 575,572.

To all whom it may concern:

Be it known that I, ERASTUS L. STOCKMAN, citizen of the United States, residing at Adams, in the county of Gage and State 5 of Nebraska, have invented certain new and useful Improvements in Portable Water Supply and Heating Systems; and I do declare the following to be a full, clear, and exact description of the invention, such as 10 will enable others skilled in the art to which it appertains to make and use the same.

This invention relates to improvements in portable water supply and heating systems.

One object of the invention is to provide 15 a portable water heating and supply system by means of which hot or cold water may be conveniently obtained for use in barber shops and other places which are not connected with city water systems or other 20 source of water supply.

Another object is to provide a portable 25 water supply and heating system adapted to be inclosed in a suitable cabinet.

With the foregoing and other objects in 30 view, the invention consists of certain novel features of construction, combination and arrangement of parts as will be more fully described and particularly pointed out in the appended claim.

35 In the accompanying drawings: Figure 1 is a perspective view showing the cabinet containing the invention; Fig. 2 is an elevation of the working parts with the tank in section; Fig. 3 is a vertical sectional view through the water supply and heating tanks; Fig. 4 is a rear elevation.

Referring more particularly to the drawings, 1 denotes a cold water tank which may be of any desired size and shape and which 40 may be filled with water in any suitable manner. Connected with the tank 1 near the bottom thereof and adjacent to one side is a water heating tank 2, which is supplied with water from the main or cold water 45 tank 1 through a water conducting pipe 3 on the end of which in the tank 2 is arranged an automatically operated supply valve 4. Connected to the valve 4 by a suitable flexible connection 5 is a valve closing 50 float 6 which, when the tank 2 is full or the water therein has risen to the desired point, will close the valve and thus cut off further supply of water to the tank 2 until the water therein has been lowered, at which time the

float will also lower to a greater or less extent thus permitting the valve to open, whereupon more water from the tank 1 will run into the tank 2. By means of the automatic water supply mechanism just described the level of the water in the tank 2 will be 60 constantly maintained as long as any water remains in the tank 1.

Arranged below the tank 2 is a burner 7 which may be of any desired construction and is here shown as an oil burner. To the 65 burner 7 is connected an oil supply pipe 8 leading to an oil supply tank 9 whereby fuel is supplied to the burner. In the pipe 8 is preferably arranged a valve 10 by means of which the flow of the oil to the burner is 70 controlled.

With the tank 1 is connected a water discharge pipe 11 which extends downwardly and outwardly and is provided with a draw-off faucet 12. With the tank 2 is connected 75 a discharge pipe 13 which is also provided with a faucet 14. The tanks 1 and 2 and the parts connected therewith are preferably inclosed in a suitable cabinet 15 on the front side of which is arranged a basin or lavatory 16 over which the faucets 12 and 14 are arranged. The basin or lavatory 16 is provided with a waste pipe 17 leading to a suitable waste water receptacle which may be disposed in any convenient place. The 80 cabinet 15 is provided on its rear side with suitable doors 18 whereby access may be had to the burner and tanks and the interior of the cabinet.

By means of a water system constructed 90 in accordance with the invention, hot or cold water may be conveniently supplied at places which are not connected with a water supply system and by inclosing the same in a cabinet as herein shown and described a 95 neat and attractive appearance will be presented.

From the foregoing description taken in connection with the accompanying drawings, the construction and operation of the in-100vention will be readily understood without requiring a more extended explanation.

Various changes in the form, proportion and the minor details of construction may be resorted to without departing from the principle or sacrificing any of the advantages of the invention as defined in the appended 105 claim.

Having thus described my invention, what I claim is:

A portable water supply apparatus comprising a cabinet with a basin secured to its outer face, tanks within the cabinet one being arranged at one side and below the other, a single pipe connected to both of the tanks having a valve and float in the lower tank, discharge pipes connected to the bottoms of each of the tanks having their terminals

provided with faucets arranged above the basin, and means also in the casing for heating one of the tanks.

In testimony whereof I have hereunto set my hand in presence of two subscribing witnesses.

ERASTUS L. STOCKMAN.
